UNITED STATES PATENT OFFICE.

FRANK D. WARD, OF NEW YORK, N. Y., ASSIGNOR TO SAUVAGE WARD BRAKE COMPANY, INC., A CORPORATION OF DELAWARE.

LIGHT AND LOAD BRAKE.

1,156,952.

Specification of Letters Patent. Patented Oct. 19, 1915.

Application filed May 15, 1912. Serial No. 697,356.

To all whom it may concern:

Be it known that I, FRANK D. WARD, a citizen of the United States, residing at New York, in the county of New York and State of New York, have invented certain new and useful Improvements in Light and Load Brakes, of which the following is a specification.

My invention is an improvement on the ordinary compressed air brake for railway and other cars and gives a light and load braking effect whereby a relatively light braking effect may be applied when the cars are running light and a suitably heavy effect when the cars are loaded.

The advantages of my invention will be readily apparent to those skilled in the art from an understanding of the following description in connection with the drawings. These show only one of the specific embodiments which my invention may take, and in them—

Figure 1 is an elevation of a portion of a railway brake apparatus embodying my improvement; Fig. 2 shows the devices of Fig. 1 with the parts newly positioned corresponding to the different stage of operation; Fig. 3 is a view of devices similar to Fig. 1 but introducing a modification; Fig. 4 is a perspective view of one of the parts detached; and Fig. 5 is a diagrammatic view on a smaller scale of a railway brake apparatus which embodies not only the parts shown in the previous figures but which adds thereto the other parts ordinarily found in such apparatus.

Describing now the specific devices of the drawings, I will refer first to Fig. 5 showing, as aforesaid, my improvement applied to a regular air brake installation. The brake operating cylinder and piston means 1 may be of any ordinary or preferred type, and said means are merely illustratively located in said Fig. 5. It may comprise as shown in the other figures a stationary compressed air cylinder 1^a and a piston whose rod 1^b is seen projecting through the usual extension 1^c on the end of the cylinder. 2 is my improvement consisting of a compound floating lever and its appurtenances operatively connected between the piston rod 1^b and the rod 3 forming part of the brake means for one of the car trucks. 4 is the so-called cylinder lever of the ordinary installation pivoted at one end to the cylinder

head and at the other to the rod 5 of the brake means for the truck on the other end of the car. Finally, 6 is the usual connecting rod between the two levers and is the resistance against which the floating levers operate when the compressed air cylinder is in action.

Referring now to the detail views, and in the first instance to Figs. 1 and 2, it will be seen that the compound floating lever 2 is made up of two levers 2^a and 2^b. The lever 2^a is pivoted at its respective ends to the piston rod 1^b and to the rod 3 of the brake means. The resistance is applied to the other lever 2^b in this particular embodiment of the invention by means of the usual connecting rod 6. The two levers 2^a and 2^b are fulcrumed together at 2^c by means of a pin 2^c passed through the lever 2^a and through a fork 2^d on the lever 2^b and which straddles the lever 2^a. The position of this fulcrum 2^c may vary along the levers to produce different desired leverage effects as will herein-after appear, but ordinarily it will be located somewhere between the resistance 6 and the brake means 3.

8 is a member pivoted at 8^a to the end of the lever 2^b. It has a slot 8^b in one end wherein works a pin 9 on the end of the lever 2. In fact, as will be seen from the detail view of this member 8 in Fig. 4, said member is forked to straddle the piston rod 1^b and the lever 2; and has two slots 8^b one in each leg of the fork. Further, it will be seen (Fig. 2) that the pin 9 which plays in these slots 8^b is also the same pin that pivotally connects the piston rod with the lever 2. The slots 8^b have each a locking notch 8^c adapted to receive therein the pin 9 and thereby lock together the two levers 2^a and 2^b so as to act as one, until the pin is released from the notch, whereupon it is free to travel the slots 8^b and thereby permit the lever 2^a to separate from and act independently of the lever 2^b under the impelling action of the piston rod 1^b. It is arranged that the two levers shall be locked together in this way during the first part of the piston stroke and shall be unlocked as aforesaid during the latter part of the stroke by means as follows: 8^a (Figs. 1, 2 and 4) is a tail piece on the member 8 whose face 8^b is a cam surface bearing against the cylinder-extension 1^c. As will be seen from Fig. 1, this retains the pin 9 in the locking notches 8^c and

so keeps the levers 2^a and 2^b locked together during the first part of the piston stroke from the position shown in full lines in Fig. 1 to that shown in the dotted lines and to a 5 certain position beyond these when the foot 8^c of the tail piece reaches the end of the cylinder-extension 1^c, whereupon the continued outward thrust of the piston carries the pin 9 into the elongated portion 8^b of 10 the slots, and the lever 2^a, being now unlocked from the lever 2^b, separates therefrom and for the latter part of the stroke continues on by itself as shown in Fig. 2 by 15 a new fulcrum 2^c which is nearer the brake means 3 than the old fulcrum 6^a. The result is that the leverage is increased and therefore the braking action during the latter part of the stroke is greater than it is during the first part of the stroke. Thus, 20 referring to the lever ratios shown in Figs. 1 and 2, it will be seen that when the levers 2^a and 2^b are locked together to act as one during the first part of the stroke, the fulcrum for both is about the point 6^a located 25 about mid-way between the piston rod 1^b and the brake means 3 so that the leverage is 1 to 1. But during the latter part of the stroke, as soon as the cam member 8 automatically unlocks the lever 2^a from the lever 30 2^b, then the fulcrum for said lever is shifted out to 2^c where the leverage ratio is increased to about 3 to 1 with corresponding increase in the power applied to the brakes. On the return stroke of the piston, the lever 35 2^a closes in against the lever 2^b and the pin 9 reaches the locking notches 8^c and enters them by camming the end 8^d of the member 8 outwardly from the position shown in Fig. 2 to those shown in Fig. 1, whereupon the 40 two levers become automatically locked together and remain so until again automatically separated on the next out-stroke of the piston in the manner above described.

Fig. 3 differs from the other figures 45 merely in showing a fork 10 rigid with one lever 2^b adapted to straddle the other lever 2^a when they are together, the legs of said fork and said lever 2^a having a hole through them to receive a removable pin 11 which 50 then locks the levers together until removed and does away with the multiplied leverage effect that occurs when the levers automatically separate. The pin 11 will be used to so lock the levers together when the cars are 55 running light or empty and is advantageous because to apply the multiplied leverage effect to the brakes on light cars would cause them to lock the wheels, which would thereupon slide on the rails and "flat" their peripheries. On the other hand, when the cars are loaded, then the multiplied leverage is wanted and is obtained by removing the 60 pins 11.

What I claim is:

65 1. A brake comprising in combination

brake-operating cylinder and piston means; brake means; a compound lever operatively connecting the first named means with the second, said lever being a floating lever with resistance applied thereto between its ends, 70 said lever consisting of two pivotally connected levers, to one of which the aforesaid brake means is connected, and to the other of which the resistance is applied; and means which locks said levers together to 75 act as one during the first part of the stroke of the cylinder and piston means, and which unlocks them during the latter part of said stroke.

2. A brake comprising in combination 80 brake-operating cylinder and piston means; brake means; a compound lever operatively connecting the first named means with the second, said lever being a floating lever with resistance applied thereto between its ends, 85 said lever consisting of two levers, to one of which the aforesaid brake means is connected, and to the other of which the resistance is applied, said two levers being fulcrumed together between their respective 90 connections with said brake means and said resistance; and means which locks said levers together to act as one during the first part of the stroke of the cylinder and piston means, and which unlocks them during the 95 latter part of said stroke.

3. A brake comprising in combination 100 brake-operating cylinder and piston means; brake means; a compound lever operatively connecting the first named means with the second, said lever being a floating lever with resistance applied thereto between its ends, 105 said lever consisting of two pivotally connected levers, to one of which the aforesaid brake means is connected, and to the other of which the resistance is applied; and means which locks said levers together to 110 act as one during the first part of the stroke of the cylinder and piston means, and which unlocks them during the latter part of said stroke, said last named means comprising a member pivoted to one of said levers and having a slot and pin connection with the other lever, said slot having a locking notch 115 which is occupied by the pin during the first part of said stroke and from which the pin is released during the latter part of the stroke to permit the pin to travel in the slot and thereby permit the levers to separate.

4. A brake comprising in combination 120 brake-operating cylinder and piston means; brake means; a compound lever operatively connecting the first named means with the second, said lever being a floating lever with resistance applied thereto between its ends, 125 said lever consisting of two levers, to one of which the aforesaid brake means is connected, and to the other of which the resistance is applied, said two levers being fulcrumed together between their respective 130

connections with said brake means and said resistance; and means which locks said levers together to act as one during the first part of the stroke of the cylinder and piston means and which unlocks them during the latter part of said stroke, said last named means comprising a member pivoted to one of said levers and having a slot and pin connection with the other lever, said slot having a locking notch which is occupied by the pin during the first part of said stroke and from which the pin is released during the latter part of the stroke to permit the pin to travel the slot and thereby permit the levers to separate.

5. A brake comprising in combination brake-operating cylinder and piston means; brake means; a compound lever operatively connecting the first named means with the second, said lever being a floating lever with resistance applied thereto between its ends, said lever consisting of two pivoted together levers, to one of which the aforesaid brake means is connected, and to the other of which the resistance is applied; and means which locks said levers together to act as one during the first part of the stroke of the cylinder and piston means, and which unlocks them during the latter part of said stroke, 25 said last named means comprising a member pivoted to one of said levers and having a slot and pin connection with the other lever, said slot having a locking notch adapted to be occupied by the pin, said member having a cam portion which bears against the cylinder and holds said pin in said notch during the first part of said stroke but which releases said pin into the slot and thereby unlocks the levers from each other during 30 the latter part of said stroke.

6. A brake comprising in combination brake-operating cylinder and piston means; brake means; a compound lever operatively connecting the first named means with the second, said lever being a floating lever with resistance applied thereto between its ends, said lever consisting of two levers, to one of which the aforesaid brake means is connected, and to the other of which the resistance is applied, said two levers being fulcrumed together between their respective connections with said brake means and said resistance; and means which locks said levers together to act as one during the first part 45 of the stroke of the cylinder and piston means, and which unlocks them during the latter part of said stroke, said last named means comprising a member pivoted to one of said levers and having a slot and pin connection with the other lever, said slot having a locking notch adapted to be occupied by the pin, said member having a cam portion which bears against the cylinder and holds said pin in said notch during the first part 50 of said stroke but which releases said pin

into the slot and thereby unlocks the levers from each other during the latter part of said stroke.

7. A brake comprising in combination 70 brake-operating cylinder and piston means; brake means; a compound lever operatively connecting the first named means with the second, said lever being a floating lever with resistance applied thereto between its ends, said lever consisting of two levers, one of which is pivotally connected at one end to the rod of the aforesaid piston and at the other end to the brake means, the second lever extending alongside the first lever and having the aforesaid resistance applied 75 thereto and being fulcrumed to the first lever between said resistance and the brake-means end of the first lever; and means which lock said levers together to act as one during the first part of the stroke of the cylinder and piston means, and which unlocks them during the latter part of said stroke.

8. A brake comprising in combination 80 brake-operating cylinder and piston means; brake means; a compound lever operatively connecting the first named means with the second, said lever being a floating lever with resistance applied thereto between its ends, said lever consisting of two levers, one of which is pivotally connected at one end to the rod of the aforesaid piston and at the other end to the brake means, the second lever extending alongside the first lever and having the aforesaid resistance applied 85 thereto and being fulcrumed to the first lever between said resistance and the brake-means end of the first lever; and means comprising a member pivoted to one of said levers and having a slot and pin connection 90 with the other lever, said slot having a locking notch which is occupied by the pin during the first part of said stroke and from which the pin is released during the latter part of the stroke to permit the pin to travel 95 the slot and thereby permit the levers to separate.

9. A brake comprising in combination 100 brake-operating cylinder and piston means; brake means; a compound lever operatively connecting the first named means with the second, said lever being a floating lever with resistance applied thereto between its ends, said lever consisting of two levers, one of which is pivotally connected at one end to the rod of the aforesaid piston and at the other end to the brake means, the second lever extending alongside the first lever and having the aforesaid resistance applied 105 thereto and being fulcrumed to the first lever between said resistance and the brake-means end of the first lever; and means comprising a member pivoted to one of said levers and having a slot and pin connection with the other lever, said slot having a locking notch 110

adapted to be occupied by the pin, said member having a cam portion which bears against the cylinder and holds said pin in said notch during the first part of the stroke but which releases said pin into the slot and thereby unlocks the levers from each other during the latter part of the stroke.

10. A brake comprising in combination 10
brake-operating means; brake means; and a compound lever delivering the power from the first named means to the second, said lever including two lever-members having different fulcrums so arranged that said lever acts about one fulcrum during the first 15
part of the stroke of the brake-operating means and about the other fulcrum during the latter part of said stroke.

11. A brake comprising in combination 20
brake-operating means; brake means; a compound lever delivering the power from the first named means to the second, said lever comprising two levers having different fulcrums; and means which locks said levers together to act about one of said fulcrums 25
during one part of the stroke of the brake-operating means and which unlocks them during another part of said stroke.

12. A brake comprising in combination

brake-operating means; brake means; and a compound lever delivering the power from the first named means to the second, said lever comprising two levers, one of which is operatively connected to the brake-operating means and to the brake-means, and being fulcrumed to the other lever, said other lever itself having its own independent fulcrum, and means which locks said levers together to act as one during one part of the stroke of the brake-operating means and which unlocks them during another part 40
of said stroke.

13. A brake comprising brake-operating means, brake means, and a lever delivering power from the first named means to the second named means, said lever comprising 45
two members adapted to move together and also having capacity for relative movement, and means for detachably connecting the two members of the lever in order to prevent such relative movements when desired.

In testimony whereof I affix my signature in presence of two witnesses.

FRANK D. WARD.
